UNITED STATES PATENT OFFICE.

JAMES WARREN WILSON, OF SWIFT CURRENT, SASKATCHEWAN, CANADA.

CURRYCOMB.

1,149,608.

Specification of Letters Patent. Patented Aug. 10, 1915.

Application filed March 22, 1915. Serial No. 16,069.

To all whom it may concern:

Be it known that I, JAMES WARREN WILSON, of the village of Swift Current, in the Province of Saskatchewan, Canada, have invented certain new and useful Improvements in Currycombs, of which the following is the specification.

My invention relates to improvements in curry combs and the object of the invention is to devise a comb of this class adaptable for both combing out fine dirt from the animal's coat and also for cutting away the hard dry caked mud matted in the coat and also such a comb as will allow of the dirt to pass freely through the body of the comb thereby preventing the retention of damp dirt liable to rot the comb and it consists essentially of an open comb body provided with cross bars, one edge of each bar being provided with fine teeth and the other wavy edge forming broad arc-shaped teeth, a handle pivoted to the frame so as to swing in a plane perpendicular to the upper and lower faces of the comb body and designed to automatically lock in an upward or downward inclined position at an obtuse angle to the upper or lower face of the comb as hereinabove more particularly explained by the following specification.

Figure 1, is a general perspective view of my comb showing the handle in the intermediate position. Fig. 2, is a similar view to Fig. 1 showing the handle in the position it assumes when the fine teeth of the comb are used in full lines and the position it assumes when the broad arc-shaped cutting teeth are used in dotted lines. Fig. 3, is an enlarged sectional plan detail of the connection between the handle and body of the comb.

In the drawings like letters of reference indicate corresponding parts in each figure.

1 is the body of the comb. The body 1 is formed by a frame bent up out of a strip of metal into rectangular form, the ends being connected by rivets 2. The lower edges of the end bars 3 and 4 of the frame forming the body are each provided with a series of fine teeth 5 and the upper edges with broad arc-shaped teeth 6.

7 are a series of cross bars extending across the frame parallel with the end bars 3 and 4. The ends of the cross bars 7 are provided with lugs 8 which are riveted to the side bars 9 and 10 of the frame forming the body 1. The lower edges of the cross

bars are provided with fine teeth which are similar to the teeth 5 hereinbefore described and the upper edges with broad arc-shaped teeth 12 similar to the teeth 6 hereinbefore described.

13 and 14 are plates riveted or otherwise suitably secured to the outer face of the end bar 3. The inner ends of the plates 13 and 14 are spaced apart and provided with outward portions 16 and 17. The portions 16 and 17 are preferably formed of spring metal having a tendency to spring outward.

18 is the handle provided with a flat end portion 19 fitting between the portions 16 and 17.

20 is a rivet extending through the portions 16 and 17 and through the portion 19, the portion 19 being swung upon the rivet.

21 are arc-shaped slots formed in the portions 16 and 17 concentric with the center of the rivet 20. The side walls of the slots 21 are each provided with lateral upper and lower depressions 22 and 23.

24 are T-shaped projections extending from the flattened end portion 19 of the handle 18. The head of the T-shape projection 24, when the handle is in the normal position shown in Fig. 1, serves to hold the portions 16 and 17 together against the sides of the flattened portion 19 in opposition to the resilience of such portions 16 and 17 tending to carry them outwardly.

It will thus be seen that when the handle 18 is swung upwardly into the position shown by full lines in Fig. 2 and the T-shape heads 24 brought opposite to the depressions 22 that the portions 16 and 17 will spring outwardly so that the inner edges of such T-shape heads 24 enter the depressions 22 and lock the handle in place. Similarly

when the handle is forced down into the dotted position shown in Fig. 2 the T-shape head enters the depressions 23 thereby locking the handle in place. When the handle is in the position shown in full lines in Fig. 2 the fine teeth of the comb are used. When it is necessary to use the reverse side of the comb, that is to say, the broad teeth 6 for cutting away the caked mud from the animal's coat the handle is forced into the position shown by dotted lines in Fig. 2 which is the position convenient for the use of these teeth.

It will, of course, be understood that the side walls of the depressions 22 and 23 are slightly inclined so as to allow of the T-heads 24 springing the portions 16

and 17 together when the handle is forced from one position to the other. It will also be seen that by the open construction of comb that all dirt removed from the animal's coat will pass directly through the comb body and will not be retained thereby. In combs in which a solid back is used the dirt accumulates in the back between the teeth and if the dirt is damp the retention of such dirt within the comb back tends to rot the comb and thus destroy its usefulness.

What I claim as my invention is.

1. In a curry comb, the combination with the comb body, of a spring plate projection extending outwardly from the body, an arc-shape slot therein, a handle pivoted to the spring plate concentric with the center of the slot, and a headed portion extending from the handle through the slot so as to bear against the outer face of the spring plate.

2. In a curry comb, the combination with the comb body, of a spring plate projection extending outwardly from the body, an arc-shape slot therein, a handle pivoted to the spring plate concentric with the center of

the slot, a headed portion extending from the handle through the slot so as to bear against the outer face of the spring plate, and depressions formed at the upper and lower end of the slot into which the headed projection is carried by the spring of the plate.

3. In a curry comb, the combination with the comb body, of a pair of spring plate projections extending outwardly from the comb body and having arc-shape slots formed therein, a handle for the comb provided with a flattened end fitting between the spring plates, a rivet extending through the spring plates concentric with the center of the slots and on which the flattened end of the handle is swung, and headed projections extending from the flattened end of the handle through the slots so that the heads thereof bear against the outer face of each plate at each side of each slot.

JAMES WARREN WILSON.
